UNITED STATES PATENT OFFICE.

OLAUS C. WOLD, OF CHICAGO, ILLINOIS.

AIR-BRUSH.

1,272,752.

Specification of Letters Patent. Patented July 16, 1918.

Application filed July 6, 1917. Serial No. 178,901.

To all whom it may concern:

Be it known that I, OLAUS C. WOLD, a citizen of the United States, residing at Chicago, in the county of Cook and State 5 of Illinois, have invented certain new and useful Improvements in Air-Brushes, of which the following is a specification.

The present invention has to do with certain improvements in air brushes. The features of the present invention are very well adapted for use in connection with air brushes of small size, such as are used by artists and draftsmen in connection with the preparation of drawings and the tinting 15 or touching up of photographs or the like.

In order to properly control an air brush, means must be provided for controlling the flow of both the air and pigment. This ordinarily necessitates the use of two separate 20 and distinct valves. In the past there have been devised various arrangements whereby both of these valves may be controlled by the movements of a single finger, but ordinarily such control has necessitated one finger 25 movement for one of the valves and another finger movement for the other valve. For example, in one form of air brush with which I am familiar, one of the valves is controlled by an up and down movement of 30 the finger, whereas the control of the other valve is effected by a back and forth movement of said finger. The necessity of using two separate finger movements for these valves is objectionable, because it makes the 35 operation of the air brush just that much more complicated. When the draftsman or artist is using the air brush he should be freed from any unnecessary thought as to the mechanical operation of the device, and 40 should be at liberty to concentrate his entire attention on the artistic appearance of the work in hand.

The main object of the present invention is to so construct the valves and actuating 45 devices that both of the valves can be controlled by a single movement of a single finger, while at the same time preserving the independence of actuation of the valves which is desirable in order to correctly control both the air and pigment.

In this connection another object is to so arrange the various parts that the control of the valves can be effected by the fore-finger of the hand and with a movement

which will be perfectly natural and normal. 55 By thus arranging the parts, the brush can be held in the hand in the same manner as the operator would hold a pen or pencil, and the movements of both of the valves can be independently controlled by a perfectly natural up and down movement of 60 the fore-finger.

Other objects and uses of the invention will appear from a detailed description of the same which consists in the features of 65 construction and combinations of parts hereinafter described and claimed.

Referring to the drawing:

Figure 1 shows a side elevation of an air brush embodying the features of the present 70 invention and shows the manner in which the same is intended to be grasped by the hand of the operator;

Fig. 2 shows on considerably enlarged scale a longitudinal vertical section through 75 the complete air brush; and

Fig. 3 shows a fragmentary plan view of the front portion of the air brush on a scale substantially the same as that of Fig. 1.

The body portion of the air brush comprises a cylindrical or tubular member 5 having a depending lug or the like 6. A cylindrical handle 7 of ebony or the like is provided, a threaded nipple or sleeve 8 serving to connect said handle to the end portion of the body member 5. This body member is hollow and accommodates the major portion of the operating mechanisms or devices. Frequently also the handle 7 will have its inner end hollowed out, as shown 85 in Fig. 2, so as to accommodate a portion 90 of the operating devices.

The front end of the body portion receives a cone-shaped sleeve 9 which threads into it, and a nipple or the like 10 threads 95 into the cone-shaped sleeve 9. A neck 11 extends upwardly from the body portion, the said neck carrying at its extreme end a tapered tip 12. The neck and tip are provided with a central longitudinal bore through which the pigment is discharged. A pin or rod 13 extends throughout the length of this bore, and is of smaller size than the bore, so that the pigment can travel 100 through the annular space thus provided. The end portion 14 of the pin is very finely pointed and seats nicely in the tip 12, so that when the pin is thrown in the forward 105

portion shown in Fig. 2, it closes the orifice and prevents the further delivery of pigment. By withdrawing the pin a greater or less amount the flow of pigment can be 5 readily controlled.

The annular space previously mentioned communicates near its rear end with a side-wise extending passage 15 into which is connected the pigment well or holder 16 by 10 way of a neck 17 in the usual manner.

The cone-shaped sleeve 9 and the front portion of the cylindrical member 5 are so formed as to leave an annular passageway 18 between them. Furthermore, the nipple 15 10 is of such size and formation as to provide a passage for the delivery of air from the passage 18 to an annular passage 19 around the tip 12. The nipple 10 has a perforation in its end portion to provide an 20 annular passage 20, through which the air is discharged around the front end portion of the tip 12 so as to induce the delivery of pigment.

The lug 6 carries the air valve mechanism. 25 The same is conveniently mounted within a collar 21 threaded into the lower end of the lug. Said collar has a longitudinal bore 22 communicating with a bore 23 in the body member 5 through which the air is delivered 30 to the annular space 18. A valve pin 24 works within the bore 22, carrying the valve member 25 at its lower end. A spring 26 normally seats within said valve member and raises the pin 24. The lower end 27 of 35 the lug 6 is threaded for the accommodation of the hose through which the compressed air or other gas is delivered.

Certain of the mechanisms thus far described are well known and understood in 40 the art. On the upper end of the pin 24 is mounted a bifurcated or slotted member 28 through which passes the pin 13. A slot or recess 29 is formed in the upper portion of the body member 5 for the accommodation 45 of a bifurcated lever 30 which is pivoted by means of a pin 31 to the lugs 32 and 33 on the body member 5. A lever 34 works within the slot or bifurcation of the lever 30 and is also pivoted or hinged on the pin 31. A 50 finger piece 35 is mounted on the lever 34 at a point where it can be conveniently reached by the fore-finger of the operator's hand as is clearly shown in Fig. 1.

The lever 34 rests on the upper end of the 55 pin 24 or the bifurcated member 28, so that the spring 26 by raising the pin 24 will also raise the lever 34 into the position shown in Fig. 2. A further raising of the lever 34 is prevented by engagement of its upper rear corner 36 against the cross piece of the bifurcated member 30.

Threaded into the rear portion of the member 5 is a collar 37 having a flange or sleeve 38. This collar 37, by reason of its 60 threaded engagement with the member 5,

constitutes a fixed abutment against which is pressed one end of a spiral spring 39. The other end of said spring presses against a flange 40 on the sleeve 41, which sleeve is loosely mounted on the pin 13, but may be 70 clamped to said pin, so that the sleeve 41, flange 40, and pin 13 will thereby be caused to travel together. Said clamp is accomplished by splitting the end portion 42 of the sleeve 41, and threading a taper or 75 wedge-shaped sleeve 43 onto said split portion.

By reason of the adjustment feature just above explained, it is possible to set the pin 13 back and forth with respect to the flange 80 40, so that the tip 12 will be opened and closed in a definite relationship with respect to the position of the flange 40.

Extending upward from the flange 40 is a pair of wings 44 (only one being shown in 85 Fig. 2, the other being cut away), between which wings lie the fingers 45 extending down from the bifurcations of the lever 30, (only one of said fingers 45 being shown in Fig. 2), so that the fingers 45 press against 90 the flange 40 and force the same back when the bifurcated lever 30 is depressed, to thereby withdraw the pin 13 from the tip 12 and permit the discharge of pigment.

On the rear end of the bifurcated lever 30 95 is a finger 46 into which is threaded a milled wheel 47, the lower portion of which carries a stud which rests against the upper face of the member 5. By turning this milled wheel, the forward end of the lever 30 may 100 be forced down so as to force back the flange 40 a greater or less extent, and thereby position the pin 13 in its forward position. By this arrangement an additional adjustment can be secured from time to time by the 105 operator without having to resort to the expedient of removing the ebony handle 7 and loosening up the taper or wedge-shaped sleeve 43.

The operation of the device will now be 110 readily understood. When the finger depresses the finger piece 35, the valve 25 is forced down against the action of the spring 26. The finger piece 35 is so formed that it presently engages with the bifurcated lever 115 30 after which time the lever 30 travels with the finger-piece, and causes the pin 13 to withdraw from the tip 12 so as to permit the discharge of pigment. Thus the air is first delivered and afterward the pigment delivery is allowed to commence, and the amount of opening of the needle valve 13 can be adjusted from time to time simply by depressing the finger-piece 35 to a greater or less extent.

By reason of the adjustment device 47, it is possible to so set the needle valve in the first instance that pigment will commence to discharge immediately upon commencing the delivery of air. Under ordinary circum- 130

stances, the parts will be so adjusted that the delivery of air commences before the pigment is allowed to be discharged.

I claim:

- 5 1. In an air brush, the combination of a body portion having suitable air and pigment orifices in its end, an air valve for controlling the delivery of air to the air orifice, a needle valve for controlling the delivery of 10 pigment from the pigment orifice, a spring tending to normally close the needle valve, a spring normally tending to close the air valve, a finger-piece pivoted to the body portion in position for engagement by the 15 fore-finger of a hand grasping the body portion, said finger-piece lying substantially parallel to the body portion, an operative connection from the finger-piece to the air valve, a bell crank lever pivoted to the body 20 portion and having one arm adapted to actuate the needle valve against its spring, and having another arm lying substantially parallel to the finger-piece, and adapted for engagement by the finger-piece after a pre- 25 determined amount of lost motion in the movement of the finger-piece, and means for limiting the backward movement of the needle valve and its lever under the impulse of its spring, substantially as described.
- 30 2. In an air brush, the combination of a body portion having air and pigment discharge orifices in its end portion, an air valve for controlling the delivery of air to the air orifice, a needle for controlling the 35 delivery of pigment to the pigment orifice, springs normally closing said valves independently, a finger-piece lying substantially parallel to the body portion and mounted for articulation only toward and from the axis of 40 the body portion by the up and down movement of the fore-finger of a hand grasping the body portion, suitable connections from said finger-piece to both the air valve and needle valve for successively actuating them 45 by such articulation against the impulses of their springs to first open the air valve and then the needle valve, and means for limiting the closing movement of the needle valve under the impulse of its spring, substantially 50 as described.
3. In an air brush, the combination of a body portion having air and pigment orifices in its end portion, air and needle valves for said orifices respectively independent springs for said valves tending to close them, 55 a finger-piece mounted on the body portion for articulation only toward and from the axis thereof by the direct movement of the fore-finger of a hand grasping the body portion, and connections from said finger-piece to both the air valve and needle valve for successively opening them against the impulses of their springs by a single direct movement of the finger-piece toward the axis 60 of the body portion to first open the air valve and then the needle valve, substantially as described.
4. In an air brush, the combination of a body portion having air and pigment orifices in its end portion, independent valves 70 for controlling the flow of air and pigment to said orifices respectively, independent springs tending to close said valves, a finger-piece mounted for articulation only toward and from the axis of the body portion by the 75 direct movement of a finger of the hand grasping the body portion toward and from the axis thereof, and operative connections from said finger-piece to the air and pigment valves for operating them in sequence by 80 the direct movement of said finger toward and from the axis of the body portion, substantially as described.
5. In an air brush, the combination of a body portion suitably formed for the 85 delivery of air and pigment from its end portion, independent air and pigment valves for controlling the delivery of the air and pigment, independent springs for normally closing said valves, a finger-piece on the 90 body portion mounted for articulation only toward and from the axis of the body portion by a single movement of a finger of the hand grasping the body portion, and operative connections from the finger-piece to 95 both of the valves for operating them in sequence by such articulation to successively open the air valve and then the needle valve, substantially as described.

OLAUS C. WOLD.
